UNITED STATES PATENT OFFICE.

AGATHA C. S. GATTI, OF CHICAGO, ILLINOIS.

ATTACHMENT FOR AUTOMOBILE TAIL LAMPS.

Application filed February 26, 1925. Serial No. 11,835.

To all whom it may concern:

Be it known that I, AGATHA C. S. GATTI, a citizen of the United States, residing at Chicago, in the county of Cook and State 5 of Illinois, have invented certain new and useful Improvements in Attachments for Automobile Tail Lamps; and I do hereby declare the following to be a full, clear, and exact description of the invention, such as 10 will enable others skilled in the art to which it appertains to make and use the same.

This invention relates to attachments for automobile tail lamps, and has for one of its objects the provision of a novel and 15 simple device of this character adapted to be illuminated by the light rays passing through the lateral or side opening of a tail lamp whereby to increase the visibility of the lamp or illuminate advertising matter.

With the above and other objects in view, the invention consists of the construction, combination and arrangement of parts hereinafter fully described and claimed, and illustrated in the accompanying drawing, 20 wherein:

Figure 1 is an elevational view illustrating the application of the attachment to an automobile tail lamp,

Figure 2 is a sectional view taken on a 30 plane extending vertically and centrally through the lamp and attachment,

Figure 3 is a sectional view taken on a plane extending horizontally and centrally through the lamp and attachment, and

Figure 4 is a detail perspective view of the attachment.

Corresponding and like parts are referred to in the following description, and designated in the several views of the drawings, 35 by similar reference characters.

In the drawing 1 designates the body, 2 the lens, 3 the electric bulb, and 4 the lateral or side opening of a well known type of automobile tail lamp.

The attachment comprises a casing 5 which, while it may be of any suitable contour, is preferably of crescent formation in outline and which embodies a concavo-convex rear wall 6, a concavo-convex front wall 7 and an arcuate inner side wall 8. The rear wall 6 and the front wall 7 are arranged with their concave sides in opposition, the

former being opaque and preferably made of metal and the latter transparent or translucent and preferably made of celluloid. 55 The rear wall 6 is provided with an inner reflecting surface, and it and the side wall 8 are provided with flanges 9 and 10, respectively, to removably secure the front wall 7 in place. The side wall 8 is provided 60 between the walls 6 and 8 with an opening 11 and is terminally provided with barrels or sleeves 12. This wall is preferably made of metal and the end portions thereof are rolled to provide the barrels or sleeves 12. 65 Arcuate attaching members or clamps 13 are pivotally connected to the side wall 8 through the medium of journals 14. Each clamp 13 and its journal 14 are preferably made from a single length of wire, and the 70 free end of the clamp is provided with an eye or loop 15 and the corresponding end of the journal with a retaining element 16.

The attachment is adapted to be secured to the tail lamp by means of the clamps 13 75 and a bolt 16 passing through the eyes 15 in a manner to position the opening 11 in the side wall 8 of the attachment in registration with the opening 4 in the side wall of the lamp. The rays of the electric bulb 3 passing through the openings 4 and 11 will be reflected by the rear wall 6 through the front wall 7. The front wall 7 may if desired be colored and may if desired be provided with the name of an automobile or any other advertising matter. As the attachment extends laterally from and is illuminated by the electric bulb thereof, it increases the visibility of the tail lamp. As is readily apparent, the attachment may be easily and 80 quickly applied to or removed from the tail lamp, and is simple, durable and inexpensive.

It should be understood that the drawing is merely illustrative and does not pretend to give exact proportions. Furthermore, the said drawing is illustrative of a preferred construction, it being my expectation that various changes and modifications may be made without departing from the spirit 90 and scope of the invention.

What is claimed is:—

1. A lamp attachment comprising concavo-convex front and rear walls of cres-

cent formation in outline, an arcuate side wall provided between said front and rear walls with an opening, and means adapted to secure the attachment to a lamp.

5 2. A lamp attachment comprising concavo-convex front and rear walls of crescent formation in outline, an arcuate side wall

provided between said front and rear walls with an opening, and arcuate clamps pivotally connected to said side wall.

In testimony whereof I affix my signature.

AGATHA C. S. GATTI.
